UNITED STATES PATENT OFFICE.

SIMON P. FULLINWIDER, OF WASHINGTON, DISTRICT OF COLUMBIA, ASSIGNOR TO
GOVERNMENT OF THE UNITED STATES.

SUBMARINE MINE.

1,372,617.

Specification of Letters Patent. Patented Mar. 22, 1921.

Application filed January 26, 1918. Serial No. 214,011.

To all whom it may concern:

Be it known that I, SIMON P. FULLINWIDER, a citizen of the United States, residing at Washington, in the District of Columbia, have invented certain new and useful 5 Improvements in Submarine Mines, of which the following is a specification.

This invention relates to submarine mines, and more particularly to safety devices 10 therefor. While especially adapted for use in connection with electrically fired mines, it will appear obvious from the disclosure hereinafter set forth, that various features of the invention are equally valuable to other 15 forms of mines. By way of illustration, the invention will hereinafter be described with relation to that particular type above-mentioned.

One of the objects of the present invention 20 is to provide a safety mechanism for submarine mines of simple and practical construction. A further object is to provide a safety device or mechanism associated with a firing mechanism so constructed, positioned and arranged as to prevent premature 25 explosion. A further object is to provide a mechanism of the last above-mentioned type which will be reliable in use and operation, and have relatively few parts 30 which may be easily, quickly made and assembled. Other objects will be in part obvious from the annexed drawings and in part indicated in connection therewith by the following analysis of this invention.

This invention accordingly consists in the 35 features of construction, the combination of parts, and in the unique relations of the various members and in the relative proportioning and disposition thereof; all as more 40 completely outlined herein.

To enable others skilled in the art so fully 45 to comprehend the underlying features thereof that they may embody the same by the numerous modifications in structure and relation contemplated by this invention, drawings 50 depicting a preferred form have been annexed as a part of this disclosure, and in such drawings, like characters of reference denote corresponding parts throughout all

the views, of which:

Figure 1 is a sectional elevational or longitudinal view of such parts of a mine, in safety position, as are necessary to fully understand the same.

Fig. 2 is a similar view showing the same 55 parts in firing position.

In order that a clearer conception of the present invention may be had, it is to be noted that certain types of submarine mines of that character commonly used in harbor 60 protection are electrically controlled or fired, and may be said to comprise a relatively large casing containing a charge of high explosive. Centrally disposed with respect to this charge, is positioned a smaller charge, 65 or primer charge, consisting of a more easily ignited explosive, such for example, granular T. N. T. This primer charge is exploded in turn by a detonator of any desired type. In the present case an electrically operated 70 one is used. The explosive material used in the detonator is sometimes less stable than the primer charge and premature explosions have occurred. Tests and experiments have demonstrated that the usual detonator will 75 not explode the primer charge or the main charge if it is more than two inches therefrom at the moment of detonation. Therefore the present invention is directed more particularly to mechanism for maintaining 80 the detonator at more than two inches from the primer charge until after the mine has been anchored and placed in operative position and then automatically set the same.

Referring now to the drawings in detail, 5 85 denotes the shell of a submarine mine, preferably of the character or type above set forth, and within which is positioned a cylindrical chamber 6 inclosing the primer charge envelop 7, usually containing granular 90 T. N. T. This envelop 7 normally occupies a fixed position within the chamber 6.

There is indicated at 8 a detonator carried 95 at one end of a linkage system 10, the opposite end of which is connected to a slideable member or piston stem 11 adapted to be actuated by a flexible diaphragm 12. These parts are so positioned and arranged that on actuation or movement of the diaphragm 100 the detonator 8 is automatically moved a much greater distance or from the position shown in Fig. 1 to that shown in Fig. 2.

The details of this construction, as clearly 105 shown in the drawings, comprises a relatively flat and slightly concaved member 13 bolted or otherwise rigidly and permanently secured to the shell 5 by means of studs 14.

Opposite the plate 13 is a concave plate 15 also secured by the same fastening means 14 and the diaphragm 12 is clamped therebetween. The central part of the diaphragm 5 is firmly held between plates 16 and 17 threaded upon the stem 11. These parts are corrugated to provide a water tight connection and held in clamping position by nut 18. The member 17 closely fits the interior of the 10 concaved portion of the member 13 and is guided and limited in movement thereby.

An annular ring 19 is secured to the member 15 in any desired manner and is adapted to contain a soluble bushing 23 of any 15 suitable material adapted to dissolve within a predetermined time, from two to twenty minutes, after being exposed to the action of sea water. This bushing is for the purpose of closing a plurality of holes 21 in 20 the plate 15 leading to the hydrostatic chamber 22. A washer 20 loosely fitting within the annular member 18 coacts therewith to protect this bushing 23 from spray or rain during transportation, and also provides 25 an abutment or point of reaction for an auxiliary safety device such as a spiral spring 24 surrounding the stud 11. This washer 20 is held in place by means of a nut 25.

30 From this it will be seen that when the mine is submerged, the sea water acts upon the bushing 23 to dissolve the same, after which it enters the hydrostatic chamber 22 between the plates 13 and 15 to move the 35 diaphragm 12, thus forcing the stem 11 inwardly with respect to the shell casing 5. Such inward movement will operate the linkage 10, which in the present case comprises what is usually referred to as lazy 40 tongs. This is so proportioned as to convert a quarter-inch movement of the stud 11 into a movement of approximately two and one-half inches of the detonator. Of course, other forms of distance multiplying 45 devices may be used, but I prefer to employ lazy tongs in view of their simplicity and reliability.

Such actuation of the lazy tongs causes the detonator 8 to move into a concave receptacle 26 centrally disposed within the 50 primer charge envelop 7. This envelop is provided with a tube 27 through which electric wires 28 may pass to the control station or other source of electric power.

55 While the primer envelop is herein shown as being rigidly supported within the chamber 6 by means of supporting members 30 and 31 at its opposite ends, it is of course to be understood that this mechanism might 60 be reversed; that is the primer envelop might be positioned at the end of the lazy tongs where the detonator is shown and the detonator could be relatively fixed with respect to the mine, provided the general objects 65 of the invention stated were accom-

plished, that is of normally keeping the detonator and primer charge in safety relation prior to the launching of the mine.

From the above it is believed that the construction, method of use and operation of 70 the device herein shown and described will be clear to those skilled in the art. It is exceedingly simple, practical and reliable in construction and operation, and the safety devices permit the mine to be handled without 75 danger of premature explosion. If for any reason a premature explosion of the detonator should occur during handling there would be little or no danger of causing the explosion of the complete mine. The 80 detonator 8 cannot be moved into the position shown in Fig. 2 without first destroying the soluble bushing 23. If this bushing should become destroyed, the expansion 85 spring 24 will normally hold the parts in the position shown in Fig. 1. It is therefore always necessary to submerge the mine to such depth as to overcome the action of this spring and cause the actuation of the 90 hydrostatically operated diaphragm before the detonator can be moved in to and maintained in position sufficiently close to the primer envelop as to cause an explosion of the mine when the detonator is fired.

A further and most important safety feature of this invention lies in the fact that, if a mine so fitted should break adrift from its moorings or for any other reason rise to the surface or in close proximity thereto the detonator would be retracted by the 100 spring 24 and the mine thereby rendered safe. In brief, a mine fitted into this device will be harmless unless and until submerged to a predetermined depth.

It is therefore believed that the present 105 invention accomplishes, among others, all of the objects and advantages herein set forth.

Without further analysis, the foregoing will so fully reveal the gist of this invention that others can by applying current 110 knowledge readily adapt it for various applications without omitting certain features that, from the standpoint of the prior art, fairly constitute essential characteristics of the generic or specific aspects of this invention, and therefore such adaptations should and are intended to be comprehended within the meaning and range of equivalency of the 115 following claims:—

I claim as my invention:—

1. In a submarine mine, in combination, a primer charge envelop, a detonator in normal safety position with respect thereto, and hydrostatically operated distance multiplying means adapted to produce relative 125 movement between said detonator and the primer charge envelop.

2. In a submarine mine, in combination, a primer charge envelop, a detonator in normal safety position with respect thereto, 130

and hydrostatically operated distance multiplying means including a lazy tong linkage adapted to produce relative movement between said detonator and the primer 5 charge envelop.

3. In a submarine mine, in combination, a casing, a primer charge envelop within said casing, a detonator normally held in safety position with respect to said primer 10 charge envelop, a diaphragm, and means between said diaphragm and said detonator adapted to move said detonator into close proximity to said primer charge envelop when said diaphragm is subjected to hydro- 15 static pressure.

4. In a submarine mine, in combination, a primer charge envelop, a detonator normally occupying a safety position, a hydrostatically actuated member adapted to produce 20 relative movement between said detonator and the primer charge envelop on submergence of the mine, and safety means associated with said hydrostatically actuated member adapted to prevent actuation 25 thereof until said mine has been submerged a predetermined time and to a predetermined depth.

5. In a submarine mine, in combination, a primer charge envelop, a detonator normally occupying a safety position, a hydrostatically actuated member adapted to produce 30 relative movement between said detonator and the primer charge envelop on submergence of the mine, and safety means including a soluble member associated with said hydrostatically actuated member adapted to prevent actuation thereof until said mine has been submerged to a predetermined depth and a predetermined time.

40 6. In a submarine mine, in combination, a primer charge envelop occupying a fixed position in the mine, a detonator normally held at safe distance therefrom, a hydrostatically actuated piston, and distance multiplying means interposed between said piston and said detonator adapted to move said detonator into close proximity to said primer charge on movement of said hydrostatic piston.

50 7. In a submarine mine, in combination, a primer charge envelop normally occupying a fixed position in the mine, a detonator normally held at safe distance therefrom, a hydrostatically actuated piston, a distance multiplying means interposed between said piston and said detonator adapted to move said detonator into close proximity to said primer charge on movement of said hydrostatic piston, and means protecting said 55 piston from the actuation of the water surrounding the mine for a predetermined time after said mine has been submerged.

60 8. In a submarine mine, in combination, a primer charge envelop normally occupying a fixed position in the mine, a detonator

normally held at safe distance therefrom, a hydrostatically actuated piston, a distance multiplying means interposed between said piston and said detonator adapted to move said detonator into close proximity to said 70 primer charge on movement of said hydrostatic piston, means protecting said piston from the actuation of the water surrounding the mine for a predetermined time after said mine has been submerged, and an auxiliary safety device associated with said piston adapted to hold said detonator in safety position until positively moved out of such position by hydrostatic pressure.

9. In a submarine mine, in combination, 80 a casing, a primer charge envelop within said casing, a detonator normally held in safety position with respect to said primer charge envelop, a diaphragm, and distance multiplying means between said diaphragm 85 and detonator adapted to move said detonator into close proximity to said primer charge envelop when said diaphragm is subjected to hydrostatic pressure.

10. In a submarine mine, in combination, 90 a casing, a primer charge envelop within said casing, a detonator normally held in safety position with respect to said primer charge envelop, a diaphragm, distance multiplying devices between said diaphragm 95 and the detonator adapted to move said detonator into close proximity to said primer charge envelop when said diaphragm is subjected to hydrostatic pressure, and spring means normally opposing said movement. 100

11. In a submarine mine, in combination, a casing, a primer charge envelop within said casing, a detonator normally held in safety position with respect to said primer charge envelop, a diaphragm, distance multiplying devices between said diaphragm and the detonator adapted to move said detonator into close proximity to said primer charge envelop when said diaphragm is subject to hydrostatic pressure, spring means 110 normally opposing said movement, and soluble means normally preventing the actuation of said diaphragm until after said mine has been submerged for a predetermined time. 115

12. In a submarine mine, in combination, a casing adapted to hold a primer charge envelop in fixed position, a detonator within said casing normally occupying a safety position with respect to said envelop, hydrostatically actuated means connected with said detonator having a chamber and comprising a diaphragm open to the action of water pressure when submerged, and a linkage interposed between said diaphragm and detonator adapted to move said detonator into close proximity to said primer charge envelop when said hydrostatic means is actuated. 120

13. In a submarine mine, in combination, 130

- a casing adapted to hold a primer charge envelop in fixed position, a detonator within said casing normally occupying a safety position with respect to said envelop, hydrostatically actuated means connected with said detonator having a chamber and comprising a diaphragm open to the action of water pressure when submerged, and a linkage interposed between said diaphragm and detonator adapted to move said detonator into close proximity to said primer charge envelop when said hydrostatic means is actuated, said chamber having openings communicating with the exterior of the mine, and soluble means normally closing said openings.
14. In a submarine mine, in combination, a casing adapted to hold a primer charge envelop in fixed position, a detonator within said casing normally occupying a safety position with respect to said envelop, hydrostatically actuated means connected with said detonator having a chamber and comprising a diaphragm open to the action of water pressure when submerged, and linkage interposed between said diaphragm and detonator adapted to move said detonator into close proximity to said primer charge envelop when said hydrostatic means is actuated, said chamber having openings communicating with the exterior of the mine, spring means associated with said hydrostatically actuated member adapted to resist accidental movement thereof, and a soluble bushing inclosing said spring means and normally closing the openings leading into said chamber.
15. In a submarine mine, in combination, a casing adapted to hold a primer charge envelop in fixed position, a detonator within said casing normally occupying a safety position with respect to said envelop, hydrostatically actuated means connected with said detonator having a chamber and comprising a diaphragm open to the action of water pressure when submerged, and linkage interposed between said diaphragm and detonator adapted to move said detonator into close proximity to said primer charge envelop when said hydrostatic means is actuated, said chamber having openings communicating with the exterior of the mine, spring means associated with said hydrostatically actuated member adapted to resist accidental movement thereof, a soluble bushing inclosing said spring means and normally closing the openings leading into said chamber, and means whereby said detonator may be connected with an electrical source of power for exploding the mine.
16. In a submarine mine, in combination, a primer charge envelop, a detonator in normal safety position with respect thereto, hydrostatically operated means adapted to produce relative movement between said detonator and the primer charge envelop when said mine has been submerged a predetermined distance, and means for separating said parts as the degree of submergence decreases.
17. In a submarine mine, in combination, a primer charge envelop, a detonator in normal safety position with respect thereto, hydrostatically operated distance multiplying means adapted to produce relative movement between said detonator and the primer charge envelop when said mine has been submerged, and spring means adapted to separate said envelop and detonator when the degree of submergence decreases.
18. In a submarine mine, in combination, a primer charge envelop occupying a fixed position, a detonator, hydrostatically actuated means for moving the detonator into close proximity to said envelop as the mine is submerged, and means for returning the detonator to normal safety position in case said mine breaks away and assumes a floating position.
19. In a submarine mine, in combination, a primer charge envelop, a detonator in normal safety position with respect thereto, hydrostatically operated means having a diaphragm adapted to produce relative movement between said detonator and the primer charge envelop when submerged a predetermined distance, and means for separating said parts as the degree of submersion decreases.
20. In a submarine mine, in combination, a primer charge envelop, a detonator normally occupying a safety position with respect thereto, a water tight casing, an hydraulically actuated member externally of the casing, and means in said casing between said hydraulically actuated member and said detonator adapted to produce relative movement between said detonator and the primer charge envelop when the hydraulically actuated member is actuated upon submersion of the mine.
21. In a submarine mine, in combination, a primer charge, a detonator in normal safety position remote from said primer charge with respect thereto and hydrostatically operative means adapted to produce relative movement between said detonator and the primer charge.
22. In a submarine mine, in combination, firing means in normally inoperative condition, a movable member adapted to be moved hydraulically to place said firing means in an armed condition, and means including a soluble member adapted to prevent movement of said movable member until said mine has been submerged a predetermined time.
- Signed at Washington, D. C., this 25th day of October, 1917.

SIMON P. FULLINWIDER.
